UNITED STATES PATENT OFFICE.

ARTHUR W. GROSS AND GEORGE H. DANNENBERG, OF SCHENECTADY, NEW YORK.

BOTTLE CLOSURE AND PROTECTOR.

1,137,607.

Specification of Letters Patent. Patented Apr. 27, 1915.

Application filed June 6, 1914. Serial No. 843,469.

To all whom it may concern:

Be it known that we, ARTHUR W. GROSS and GEORGE H. DANNENBERG, citizens of the United States, residing at Schenectady, in the county of Schenectady and State of New York, have invented new and useful Improvements in Bottle Closures and Protectors, of which the following is a specification.

10 An object of the invention is to provide a simple bottle closure and protector for use on bottles and similar receptacles, such as milk bottles, and in which it is desired to provide not only a closure but a protector for protecting the mouth of the bottle against germs or insects, such as flies, which might ordinarily alight upon that portion of the neck over which the fluid is poured when the bottle is placed in use.

20 The invention contemplates, among other features, the provision of a hood-like member which is adapted to be arranged over the neck of the bottle or receptacle which may or may not have its closure thereon, with suitable means of securing the hood-like member in position against accidental displacement.

25 In the further disclosure of the invention reference is to be had to the accompanying drawings, constituting a part of this specification, in which similar characters of reference denote corresponding parts in all the views, and in which:

30 Figure 1 is a fragmentary perspective view showing the device applied; Fig. 2 is a vertical sectional view taken through the bottle and closure, showing the protector applied; Fig. 3 is a horizontal sectional view taken on the line 3—3 in Fig. 2; and 35 Fig. 4 is a perspective view of the securing means formed from the protector and closure.

40 Referring more particularly to the views, we provide a bottle 10 having the usual neck 11 which may or may not be closed by a cap or cork 12. A hood-like member 13 preferably made of paper, suitably parafined, is arranged to fit over the neck to close the opening of the bottle if the same is not

provided with a cap or cork and to inclose 50 the cap or cork if the bottle is provided with one, said hood-like member having a depending portion 14 which is preferably fluted so as to fit closely around the neck. A securing member 15 is provided for the 55 hood-like member 13 and consists, more particularly, of a strip 16 preferably formed of stamped metal to provide a plurality of oppositely extending gripping lugs 17 projecting from the same side of the strip, with the 60 said strip adapted to encircle the depending fluted portion 14 of the hood-like member and thus also encircle the neck of the bottle so that the lugs will grip into the depending portion of the member, as will be readily 65 seen by referring to the views. One end of the strip is preferably bent outwardly and provided with a transverse slot 18 and the other end of the member terminates in a reduced tongue 19 which, when the strip 70 has been arranged to encircle the neck, is passed through the slot 18 and then bent rearwardly upon the body of the strip, thereby securing the strip in encircling position and holding the hood-like member 75 rigidly on the bottle.

It will be readily apparent that when it is desired to remove the hood-like member the same can be easily accomplished by bending the tongue 19 outwardly from the 80 body of the strip and then removing it from the slot 18. With the provision of a hood-like member such as described the mouth or pouring edge of the bottle will be protected from germs, dust, dirt or flies and 85 particularly when a cap or cork is not used as a closure for the bottle, the said protector will constitute a closure for the bottle as well as a protector therefor.

Having thus described our invention, we 90 claim:

95 In combination with a bottle having a neck, a hood-like member adapted to be arranged over the neck and having a depending fluted portion encircling the neck, and a securing member for securing the said hood-like member on the neck, said securing member consisting of a strip formed at

2
one end with a slot, a tongue formed at the other end of the strip and adapted to be passed through the slot when the strip encircles the neck, and a plurality of gripping lugs struck from one side of the strip and projecting in opposite directions to grip into the depending portion of the hood-like member to secure the same on the neck.

In testimony whereof we affix our signatures in presence of two witnesses.

ARTHUR W. GROSS.
GEORGE H. DANNENBERG.
